Belt Hook for Cordless Drill and Impact, posted on amazon.com, first available Sep. 17, 2014, no production date posted, [online], [site visited May 3, 2019], Available from Internet, URL: <https://www.amazon.com/Belt-Hook-Cordless-Drill-Impact/dp/B00L2DQ1UM> (Year: 2014).*

Primary Examiner — Michael C Stout*Assistant Examiner* — Fitzgerald L Butac(74) *Attorney, Agent, or Firm* — Skaar Ulbrich Macari, P.A.(57) **CLAIM**

The ornamental design for an anchor point for drill, as shown and described.

DESCRIPTION

FIG. 1 is a perspective view of an anchor point for drill showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a perspective view thereof in use.

The broken lines show portions of an anchor point for a drill that form no part of the claimed design.

1 Claim, 8 Drawing Sheets(56)
